UNITED STATES PATENT OFFICE.

JOHN KELLENBERGER, OF ROCKLAND, MAINE, ASSIGNOR OF ONE-FOURTH TO EDWARD R. BROCK AND ONE-FOURTH TO ELMER B. CROCKETT, BOTH OF ROCKLAND, MAINE.

SHIPPING-CRATE.

1,129,687.

Specification of Letters Patent. Patented Feb. 23, 1915.

Application filed September 2, 1914. Serial No. 859,831.

To all whom it may concern:

Be it known that I, JOHN KELLENBERGER, a citizen of the United States, residing at Rockland, in the county of Knox and State 5 of Maine, have invented new and useful Improvements in Shipping-Crates, of which the following is a specification.

This invention relates to shipping crates and the principal object of the invention 10 is to provide a simple, cheaply constructed and thoroughly efficient receptacle adapted essentially for shipping eggs and other fragile articles by parcel post.

Another object of the invention is to provide 15 a container of this character which will effectively protect the eggs against breakage irrespective of the position which it occupies and whether the eggs are arranged butt or point up.

20 Further objects of the invention will appear as the following description is read in connection with the accompanying drawing, which forms a part of this application, and in which:—

25 Figure 1 is a perspective view of the case. Fig. 2 is a sectional perspective view of the bottom member. Fig. 3 is a similar view of the top member. Fig. 4 is a transverse sectional view showing the members 30 assembled. Fig. 5 is a detail horizontal sectional view showing a number of the egg wrappers arranged within the case.

Referring more particularly to the drawing, 35 1 and 2 represent the bottom and top members of the receptacle, respectively. The bottom member is constructed of a flat ring 3 on which are mounted the supporting rings 6 and 7, the former being arranged adjacent the inner wall or flange while the 40 latter is arranged adjacent the outer wall or flange, thereby providing an air space 8 between the two. This space is closed by a supporting disk 9 which rests upon the rings 6 and 7 and forms a support for one 45 end of the egg. The top member comprises a flat ring-shaped member 10 having inner and outer side walls 11 and 12, the former being about one-half the width of the latter and having its lower edge preferably curled 50 outwardly to facilitate the insertion of the top member over the bottom member. The top member also has secured therein the supporting rings 13 and 14 forming an air space 15 which is covered by the ring-

shaped disk 16 forming a support for the 55 opposite end of the egg. When the eggs are placed in position they are preferably wrapped in corrugated board 17 such as is shown in Figs. 3 and 4 which also rests upon the rings 9 and 16. 60

Preferably the outer wall 5 of the lower member is provided with annular ribs 18 which space the outer wall 12 from the wall 5 and also provide a cushioning means which acts to absorb any shock and prevents the 65 same from being transmitted to the egg. The junction of the walls of both top and bottom members with the flat rings, 3 and 10 may be made by cramping the flanges of the respective members, to the walls 70 which are lengthened for the purpose, or in any other manner suitable to the material used in constructing the walls and rings 3 and 4, thus forming the annular beads 19 and 20 which protect the top and bottom 75 members and prevent these parts from being driven into engagement with the rings 9 and 16 and thus break the eggs. The top and bottom members can be fastened together by gluing or in any other suitable 80 manner which may be found to be desirable.

It will be noticed that with a container of this type that circular boxes of varying diameters may be constructed according to the size and number of the eggs to be shipped 85 and that with a container of this character having a central opening that a number may be placed upon the arm for carrying purposes.

What is claimed is:—

1. An egg shipping receptacle comprising 90 a ring-shaped receptacle, a ring-shaped cover therefor, spaced rings in the receptacle and cover, ring-shaped disks mounted upon said rings and forming abutments for 95 opposite ends of the egg, and a packing sleeve for surrounding each egg.

2. A receptacle comprising similarly 100 formed annular top and bottom members, one adapted to fit within the other, spaced rings carried in said top and bottom members, egg supporting members fitting within the members and resting upon the rings, said egg supporting members adapted to support the eggs in their transverse center 105 between the rings, and packing sleeves for surrounding the eggs.

3. A receptacle comprising similarly

formed annular top and bottom members, one adapted to fit within the other, spaced rings carried in said top and bottom members, egg supporting members fitting with-
5 in the members and resting upon the rings, said egg supporting members adapted to support the eggs in their transverse center between the rings, packing sleeves for sur-

rounding the eggs, and protecting means carried by the top and bottom members. 10

In testimony whereof I affix my signature in presence of two witnesses.

JOHN KELLENBERGER.
